CANOPY

Frank R. Thompson and William D. Bell, Akron,
Ohio, assignors to The Falls Stamping and
Welding Company, Cuyahoga Falls, Ohio, a
corporation of Ohio

Application July 27, 1950, Serial No. 176,139

3 Claims. (Cl. 20—57.5)

1

This invention relates to improvements in canopies, awnings and the like of the prefabricated type which are preferably formed of metal, and which after assembly may be quickly and easily installed over a door or other opening of a home or other building.

Among the objects of this invention are the provisions of a novel canopy construction formed of relatively few parts which may be quickly assembled by a homeowner and erected in any desired location; which is attractive, permanent and a desirable addition to a building; which though of relatively light weight is sturdy and compact; and which obviates the use of screws or the like in assembling the component parts of the canopy, although screws or other fastening means may be utilized to secure the assembled canopy to a building.

Further objects are to provide a canopy of the character referred to having arched roof sections terminating at their meeting ends with channeled portions joined together with a channeled ridge strip which may be quickly slid into position holding the roof sections together; a canopy in which each roof section is bent inwardly longitudinally thereof at spaced intervals to create an impression of a plurality of slanting strips; a canopy in which each roof section has a channeled portion adjacent its outer end to which channeled side pieces may be slidably joined; a canopy with roof sections having channeled portions adjacent their front edges to which a channeled front piece may be slidably joined; and a canopy having angled bars adjacent its rear edges which may be utilized in conjunction with a hanger plate to secure the assembled canopy to a building wall.

A further object is to provide a modified form of canopy or awning having all the features of the first form, except that the channeled front piece is omitted from the structure to allow the roof sections to be secured in arched position at various selected angles on the wall of a building.

Other objects and advantages will become apparent from the following description taken in conjunction with the accompanying drawings.

In the drawings:

Fig. 1 is a perspective view of a canopy assembled and erected in accordance with the present invention.

Fig. 2 is an enlarged section taken substantially on line 2—2 of Fig. 1.

Fig. 3 is a similar section taken substantially on line 3—3 of Fig. 1.

Fig. 4 is a similar section taken substantially on line 4—4 of Fig. 1.

2

Fig. 5 is a similar section taken substantially on line 5—5 of Fig. 1.

Fig. 6 is a partial perspective view showing the manner of assembling the roof sections with the front piece,

Fig. 7 is a similar view showing the manner of assembling the ridge strip with the roof sections,

Fig. 8 is a similar view showing the manner of assembling the side pieces with the roof sections,

Fig. 9 is a similar view of a doorway over which a canopy is to be erected with the hanger plate in position to receive the assembled canopy, and

Fig. 10 is a front elevation of a modified form of canopy or awning in which the front piece is omitted from the assembly.

Referring to the drawings, the canopy or awning shown in Figs. 1 to 9, inclusive, comprises a pair of metal roof sections, each of which is indicated as a whole by the numeral 10, and each 20 of which terminates at its upper end with an upwardly curled edge that forms a longitudinal channeled portion 11. Each roof section is bent inwardly longitudinally as indicated at 12, at a plurality of places to create the impression that each roof section is formed of a plurality of slanting strips 13, while actually each roof section is one piece of material. At its outer end, each roof section is bent backwardly upon itself, as indicated at 14 in Fig. 3, being held in such position 25 by rivets 14', or the like, and its edge is curled downwardly to form a longitudinal channeled portion 15. Adjacent the rear edge of each roof section, an angle bar 16 is secured thereto by rivets 17, or the like, and these angle bars are 30 utilized to secure the assembled canopy to a building, as will be later explained. Inwardly of its front edge, each roof section is also provided with a strip 18 secured thereto by rivets 19 or the like, that is curled downwardly to form a transverse channeled portion 20 (see Figs. 5 and 6).

A metal front piece or plate 21 of triangular shape has its two side edges curled outwardly to form channeled portions 22 which are slidably received in the channeled portions 20 of the roof sections, while its lower edge is curled inwardly to form a channeled portion 23 (Fig. 5), for the purpose of strengthening this front piece.

The front piece 21 holds the roof sections in arched position with their channeled portions 11 adjacent each other, and a metal ridge strip 24 having its longitudinal edges curled to provide a pair of channels 25 slidably receives the channeled portions 11, as indicated in Fig. 2, the arrangement being such that the ridge strip holds the roof sections in proper meeting or nearly

meeting relation, and this ridge strip also serves to prevent water leaking through the space between the adjacent edges of the roof sections.

To assist in supporting the structure on a building and to enhance its appearance, a pair of triangular metal side pieces or plates 26 are provided, the upper edge of each piece 26 being curled inwardly to provide a channeled portion 27 (Figs. 3 and 8) which is slidably received in the channeled portions 15 adjacent each side of the awning. The lower inclined edges of the side pieces 26 are also curled inwardly to provide channeled portions 28, for the purpose of strengthening these side pieces. As will be observed from Fig. 3, by having the outer end portions of the roof sections bent backwardly upon themselves in the manner shown, the side pieces 26 are permitted to hang downwardly a substantial distance inwardly from the ends of the awning, thereby allowing substantial portions of the awning to extend beyond the side pieces. The rear edge portions of each side piece 26 are cut and bent at a right angle to the body of the side piece (as indicated in Figs. 1 and 3), and are folded to double thickness as at 29 to strengthen the material, the double thick area being provided with screw receiving openings 30.

The manner of assembling the parts of the canopy is shown in Figs. 6 to 8 inclusive. First, the roof sections 13 are joined to the front piece 21 by slidably interlocking the channeled portions 20 and 22, as indicated in Fig. 6, so as to bring the roof sections into arched position with their channeled portions 11 adjacent each other. Next, the ridge strip 24 connects the roof sections together by slidably interlocking the channeled portions 11 and 25, as indicated in Fig. 7, and then the side pieces 26 are joined to the roof sections by slidably interlocking the channeled portions 15 and 27, as indicated in Fig. 8.

Fig. 9 shows the upper portion of a doorway 31 over which the canopy is to be erected, and above the upper door frame member 32 a metal hanger plate 33 is secured by screws 34 to the building or other structure in which the doorway is formed. Plate 33 has a forwardly offset portion 35 of substantially semihexagonal shape which has a forwardly directed flange 36 along its upper edges. The assembled canopy is placed in proper position by hanging the angle bars 16 behind the offset portion 35 of the hanger plate so that the bars 16 assume approximately the position indicated in Fig. 2. This will place the bars 16 approximately against the building and permit the rear edges of the side pieces 26 to be moved against the building, after which screws or the like may be inserted through the openings 30 in the side pieces and the openings 37 in the angle bars to tightly secure the canopy to the building. The broken lines 38 in Fig. 9, show approximately the area of the canopy which is in contact with the building after the canopy is properly erected.

After the canopy has been erected, a channeled drain strip 39 is preferably secured to the upper edge of the upper door frame member 32 to catch any water that may drip from the rear of the canopy.

It will be seen that the canopy is formed of relatively few parts which may quickly and easily be assembled by a houseowner and erected by him in any desired location with a minimum of effort, and without the use of screws or similar fastening means, except in the final step of securing the canopy to a building. The canopy is attractive in appearance and adds to the beauty

of a building. Also, it can be shipped in knocked down condition in a relatively small package.

In Fig. 10 we have shown a modified form of canopy or awning in which the front piece 21 is omitted. Except for the absence of this front piece, the canopy or awning parts shown in Fig. 10 with primed numbers are identical with their unprimed counterparts shown in Figs. 1 to 9, inclusive. In the modified form of the invention, 10 the roof section 10' may be arched at any desired angle (as indicated by the broken line positions in Fig. 10) by merely turning the channeled portions 11' within the channels 25' of the ridge strip 24' until the desired positions are obtained, after 15 which they are secured in such positions by fastening the angle bars 16' to the building wall. In assembling the parts of the structure shown in Fig. 10, it is preferred to first connect the roof sections 10' together by means of the ridge strip 20 24', then place the angle bars 16' behind the hanger plate which has been secured to a wall, and then secure the angle bars to the wall with the roof sections arranged at the desired angle. Lastly, the side pieces 26' are slidably connected 25 to the roof sections and the rear faces of the side pieces are secured to the wall in the same manner as the side pieces 26.

While we have shown and described the preferred embodiments of the invention, it will be 30 apparent that the invention is not limited to these embodiments, and that changes and modifications may be made therein without departing from the spirit of the invention or from the scope of the subjoined claims.

35 What is claimed is:

1. A prefabricated canopy of unitary structure comprising two like but oppositely faced roof sections of sheet metal having adjacent inner edges provided with upwardly curled longitudinal 40 channeled portions, the outer end portion of each roof section being bent backwardly against itself and terminating in a downwardly extending longitudinal channeled portion located a substantial distance inwardly from said outer ends, a ridge strip having downwardly curled channeled portions slidably interlocked with said first named channeled portions, a pair of triangular side plates each having an inwardly curled channeled portion 45 slidably interlocked with one of said second named channeled portions on the roof sections so as to allow substantial portions of said roof sections to extend beyond said side plates, and means on the roof sections adjacent the rear edges thereof 50 adapted for interengagement with anchor means on a wall, whereby the canopy may be hung in place.

2. A prefabricated canopy of unitary structure comprising two like but oppositely faced roof sections of sheet metal having adjacent inner edges provided with upwardly curled longitudinal 60 channeled portions, each roof section being also provided with a downwardly curled transverse channeled portion adjacent its front edge, the outer end portion of each roof section being bent 65 backwardly against itself and terminating in a downwardly extending longitudinal channeled portion located a substantial distance inwardly from said outer ends, a ridge strip having downwardly curled channeled portions slidably interlocked with said first named channeled portions, a triangular front plate having outwardly curled 70 channeled portions slidably interlocked with said second named channeled portions on said roof sections, a pair of triangular side plates each having an inwardly curled channeled portion slidably 75 interlocked with one of said second named channeled portions on the roof sections, and means on the roof sections adjacent the rear edges thereof adapted for interengagement with anchor means on a wall, whereby the canopy may be hung in place.

interlocked with one of said third named channeled portions on the roof sections so as to allow substantial portions of said roof sections to extend beyond said side plates, and means on the roof sections adjacent the rear edges thereof adapted for interengagement with anchor means on a wall, whereby the canopy may be hung in place.

3. A prefabricated canopy of unitary structure comprising two like but oppositely faced roof sections of sheet metal having adjacent inner edges provided with upwardly curled longitudinal channeled portions, the outer end of each roof section being bent backwardly against itself and terminating in a downwardly extending longitudinal channeled portion located a substantial distance inwardly from said outer ends, a ridge strip having downwardly curled channeled portions slidably connected with said first named channeled portions, the connection between said ridge strip and said first named channeled portions allowing said roof sections to be turnable with respect to said ridge strip to form an arch of various selected angles, a pair of triangular side plates each having an inwardly curled channeled portion slidably interlocked with one of said second named channeled portions on the roof sec-

tions so as to allow substantial portions of said roof sections to extend beyond said side plates, and means on the roof sections adjacent the rear edges thereof adapted for interengagement with anchor means on a wall, whereby the canopy may be hung in place.
